United States Patent Office

Des. 201,703
Patented July 20, 1965

201,703

TISSUE PACKAGE HOLDER

Forbes Howard, 360 Mary St., Grosse Pointe Farms, Mich.

Filed Apr. 20, 1964, Ser. No. 79,572

Term of patent 3½ years

(Cl. D52—2)

FIGURES 3 and 4 are respectively plan views showing the top and bottom thereof; and

The tissue box and supporting surface shown in broken lines in FIG. 1 are included for illustrative purposes only.

I claim:

The ornamental design for a tissue package holder, as shown and described.
